Primary Examiner — Lakiya Rogers*Assistant Examiner* — Harold Blackwell, II(74) *Attorney, Agent, or Firm* — Volpe and Koenig, P.C.(57) **CLAIM**

The ornamental design for an electrical housing, as shown and described.

DESCRIPTION

FIG. 1 is a front perspective view of the electrical housing according to my design;

FIG. 2 is a rear perspective view of the electrical housing shown in FIG. 1

FIG. 3 is a left elevation view of the electrical housing of FIG. 1, the right side being a mirror image thereof;

FIG. 4 is a top plan view of the electrical housing of FIG. 1;

FIG. 5 is a bottom view of the electrical housing of FIG. 1;

FIG. 6 is a rear view of the electrical housing of FIG. 1; and,

FIG. 7 is a front view of the electrical housing of FIG. 1. The broken lines shown in FIG. 5 form no part of the claimed design.
